UNITED STATES PATENT OFFICE

MAX SPILLMANN, OF RICHLFIELD, NEW JERSEY, ASSIGNOR TO WORTHINGTON PUMP AND MACHINERY CORPORATION, OF NEW YORK, N. Y., A CORPORATION OF VIRGINIA

CENTRIFUGAL PUMP

Application filed March 30, 1925. Serial No. 19,197.

This invention relates to improvements in centrifugal pumps.

It is the especial object of the invention to provide a pump of this type which will be strong and durable and which may be employed with advantage in handling crude petroleum and its products throughout the various stages of modern oil cracking and refining processes. The present pump, while having all the advantages of displacement pumps as now constructed for withstanding the high temperatures and pressures encountered in this use, is much cheaper to manufacture, and is fully as efficient as such displacement pumps, or even more so, and the construction is such that the operating parts are readily accessible for inspection, cleaning, replacement or repair.

In the accompanying drawings forming a part of this specification, there is shown a pump embodying all the features of the present invention in a preferred form, and this construction will now be described in detail in connection with said drawings, and the novel features of the invention then be specifically pointed out in the claims.

In the drawings—

Figure 1 is a view partly in elevation and central longitudinal section;

Figure 2 is a side elevation of the pump body; and

Figures 3 and 4 are sections, respectively, on the lines 3—3 and 4—4 of Fig. 2.

Referring now to the drawings, 10 indicates a metal pump body which, for the necessary strength and durability under the high temperatures and pressures encountered in handling petroleum and its products during the various steps of modern oil cracking and refining processes, is preferably a steel forging in which are formed all the chambers and passages hereinafter referred to. It will be understood, however, that cast steel may be substituted for such a steel forging, and this with advantageous results as compared to prior pumps constructed for high pressures or high temperature use, and with a corresponding reduction in cost. In the body 10 are formed a suction passage 11 communicat-

trally and common to the impellers herein-after referred to, together with discharge passages 13 communicating at their inner ends with discharge chambers 15 formed on opposite sides of the body 10 and preferably converging into a common outlet 16. While the discharge chambers 15 have been shown as concentrically arranged, it will be understood that a machined or forged circular chamber appropriately off-center with respect to the shaft, or other form of volute, may be used if desired. The impellers 17 preferably and as shown face each other and are mounted on shaft 19, their eyes, as above stated, being in communication with common suction chamber 12. As shown, also, the impellers have their outlets turned so as to deliver in a substantially axial direction toward each other and into their respective discharge chambers, thus not only effectually balancing axial shaft thrust, but enabling the outside dimensions of the pump to be materially reduced. The sides of the pump body 10 are closed by plates 18 which preferably are steel forgings and which may be secured to the body 10 in any suitable manner, or by screw bolts, as shown, and thus be readily removable for access to the interior of the pump body for inspection, cleaning and repair or replacement of parts. As shown, the plates 18 have integrally formed therewith the stuffing boxes and supports for the shaft bearings hereinafter referred to. The shaft 19 may advantageously be mounted in ball bearings, indicated generally at 20, supported by standards 21 mounted on the base 22. While bearings of other types may be substituted for those shown, the present bearings will not be affected by the high temperatures and may therefore be used with advantage in place of bronze or Babbitt metal bearings which have relatively low melting points. A driving pulley 23 is shown for driving the shaft, but obviously the shaft may be driving in any other suitable manner and, if desired, be direct connected to a prime mover. The impellers may not be turned to deliver axially, but deliver radially, as usual in centrifugal pumps. The walls of the discharge passages also may be

tapered, as shown, so that the passages diverge in the line of flow.

While the construction so far described will function efficiently in handling liquids generally and even hot liquids at high pressures, means are preferably provided for cooling the shaft and the stuffing boxes, so that the pump may be used in lieu of displacement pumps in handling crude petroleum and its products in the various stages of the refining processes, thus resulting in long life of these parts and enabling uninterrupted operation of the pump. To secure this result, the shaft and stuffing boxes are efficiently cooled by maintaining a supply of cold oil in chambers 3, inlets 4 thereto being provided which may be placed in communication with any suitable source of supply. Preferably, however, the cold oil in the chambers 3 is maintained under a pressure in excess of the pressure in the suction chamber 12, so that whatever leakage does occur from the chambers 3 will be toward the impellers and consequently be carried off in the discharge. A separate pump or pumps of any desired type, but preferably a displacement pump or pumps (not shown) may be employed for thus maintaining cold oil under pressure in the chambers 3. Leakage along the shaft in the opposite or outward direction and through the stuffing boxes 2, may be effectually prevented by packing of any preferred type. This means for cooling the bearings and avoiding the passage of hot liquid to the stuffing boxes is preferably used, but other cooling arrangements may be employed.

While the present construction has been described as especially suitable for use in handling liquids at high pressures and temperatures, it will be understood that the pump is well adapted for other uses, and that various changes in the construction and arrangement of parts shown and described may be made while still retaining the invention defined by the claims. The broader features of the invention may be used in a single impeller pump, and such a pump is intended to be included within such claims as are not specifically limited to impellers on opposite sides of the pump body.

What is claimed is:

1. A centrifugal pump, comprising a pump body formed of a single block having therein impeller chambers and discharge chambers on opposite sides of the block, a central suction chamber and suction passage connecting therewith and discharge passages connecting with said discharge chambers, side plates arranged to close said chambers, and an impeller shaft mounted in the side plates and carrying impellers having their suction openings facing each other, said impellers lying in planes outside the discharge chambers and having their outlets turned to

discharge at an angle to their plane of rotation.

2. A centrifugal pump, comprising a pump body formed of a single block having therein impeller chambers and discharge chambers on opposite sides of the block, a central suction chamber and suction passage connecting therewith and discharge passages connecting with said discharge chambers, side plates arranged to close said chambers, and an impeller shaft mounted in the side plates and carrying impellers having their suction openings facing each other, said impellers lying in planes outside the discharge chambers and having their outlets arranged 70 to deliver in a substantially axial direction toward each other.

3. A centrifugal pump for hot liquids, comprising a pump body formed of a single block having therein impeller chambers and discharge chambers on opposite sides of the block, a central suction chamber and suction passage connecting therewith and discharge passages connecting with said discharge chambers, side plates arranged to close said chambers, an impeller shaft mounted in the side plates and carrying impellers having their suction openings facing each other, said impellers having their outlets turned to discharge at an angle to their plane of 80 rotation, and chambers on the side plates adjacent the shaft openings arranged to enclose the shaft and receive cooling fluid under pressure in excess of the pump pressure to prevent leakage of the hot liquid at the 90 shaft bearings.

4. A centrifugal pump, comprising a pump body formed of a solid block and having impeller chambers formed in the opposite sides thereof, and having annular discharge chambers positioned at one side and inwardly from the impeller chambers, said body having an axial bore forming a suction chamber communicating with said impeller chambers and having discharge passages communicating tangentially with said discharge chambers and gradually converging towards the discharge outlet in such manner as to provide convergence of the discharge streams at a 100 relatively small angle.

5. A centrifugal pump, comprising a pump body formed of a solid block and having impeller chambers formed in the opposite sides thereof and having annular discharge chambers positioned at one side and inwardly from the impeller chambers, said body having an axial bore forming a suction chamber communicating with said impeller chambers and having discharge passages communicating tangentially with said discharge chambers and gradually converging towards the discharge outlet in such manner as to provide convergence of the discharge streams at a 110 relatively small angle, side plates closing said 120 impeller chambers, and impeller shaft mount 125 130

ed in the side plate, and chambers on the side plates adjacent the shaft openings arranged to enclose the shaft and receive cooling fluid under pressure in excess of the pump pressure to prevent leakage of liquid from the impeller chambers at the shaft bearings.

In testimony whereof, I have hereunto set my hand.

MAX SPILLMANN.
